United States Patent Office

Des. 209,954
Patented Jan. 23, 1968

209,954

BARBECUE STAND

William R. Hathorn, Jr., % Hathorn Manufacturing Co.,
2903 Chicago St. at Broadway, P.O. Box 926, Alexandria, La. 71301

Filed Sept. 12, 1966, Ser. No. 3,820

Term of patent 14 years

(Cl. D13—1)

FIG. 1

FIG. 2

FIG. 3

FIG. 4

FIG. 5

FIG. 1 is a perspective view of a barbecue stand showing my new design, the front and left hand side thereof being shown in this view;

FIG. 2 is a front view thereof;

FIG. 3 is a view of the left hand side thereof;

FIG. 4 is a rear view thereof;

FIG. 5 is a view of the right hand side thereof.

I claim:

The ornamental design for a barbecue stand, as shown and described.
